UNITED STATES PATENT OFFICE.

JAMES W. UNDERWOOD, OF SHERIDAN, INDIANA.

GAS HEATING APPARATUS.

SPECIFICATION forming part of Letters Patent No. 512,132, dated January 2, 1894.

Application filed April 5, 1893. Serial No. 469,137. (No model.)

To all whom it may concern:

Be it known that I, JAMES W. UNDERWOOD, a citizen of the United States, residing at Sheridan, in the county of Hamilton and State of Indiana, have invented certain new and useful Improvements in Gas Heating Apparatus; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to certain improvements in heating apparatuses such as are employed for heating rooms in lieu of coal or gas stoves, and its object is to provide an apparatus of this character which shall be of a simple and inexpensive construction, and one which may be conveniently and safely operated and which shall not be an obstruction to the free use of the room to be heated, all as will be hereinafter fully set forth.

25 The novel features of my invention will be carefully defined in the claims.

In the accompanying drawings illustrating my invention, Figure 1 is a vertical sectional view through the floor of the room which it is desired to heat by my improved apparatus, the heater being seen in elevation in position for use, and Fig. 2 is a similar view showing the device in section. Fig. 3 is a plan view of the device. Fig. 4 is a detail view which 35 will be referred to hereinafter.

In the views X represents the floor of the room, which is provided with an aperture α , having a suitable curb about its edge to which is hinged at one side, a register Y of open-work cast iron such as is usually provided for furnace heating flues. This register is shown in Fig. 2 as raised on its hinges to a substantially vertical position.

Z is one of the walls of the house, and z is the flue leading to the chimney. The opening α in the floor is arranged close up to the wall Z by preference and the curb of said opening is provided in its interior with a projecting ledge α' .

50 A is a metal casing preferably of square or rectangular cross section provided about its upper edges with projecting flanges a adapt-

ed to engage and rest upon the ledges α' of the curbing of aperture α , whereby said casing A is held in position below the floor of 55 the room as clearly seen in Figs. 1 and 2 of the drawings.

B is an elbow pipe passing through an opening in the wall Z into the flue z , and having its vertical branch within the casing A, which 60 it enters near the lower end thereof. Braces or stays of any suitable kind are provided for holding pipe B in its vertical position as seen in the drawings. The gas supply pipe C enters the casing A also near the lower end 65 thereof but at the side opposite to the pipe B. A valve c is provided in the gas supply pipe outside the casing and a vertical rod c' is provided for turning said valve the upper end of said rod passing through the floor adjacent to the register Y and being provided with a handle as clearly seen. Within the casing A the gas pipe C is also bent up vertically and is provided at its extremity with a burner C' of fire-clay or other durable material.

D is a combustion chamber formed with a central horizontal portion d and two depending arms d' , d^2 at its ends. The arm d' has a diameter equal to the internal diameter of 80 the vertical branch of pipe B into which it fits and is adapted to slide. The arm d^2 is of a somewhat larger diameter than the arm d' and is closed at its base so as to be practically air and gas tight.

E is a transverse brace or strut arranged midway of the chamber formed by arm d^2 through which passes a vertical burner tube bearing a burner C' of fire-clay or other suitable kind. This burner tube F extends down 90 through the closed bottom of the arm d^2 , and incloses the vertical branch of the gas supply pipe C, than which it is slightly larger in diameter so that an annular aperture is provided at its lower end for the entrance of air to 95 the burner to support combustion of the gas escaping at the tip of pipe C.

At about the center of the upper surface of the horizontal portion d of the combustion chamber D is provided a ring or loop g adapted to receive a hook on the lower end of an operating rod G seen in detail in Fig. 4, by means of which the chamber D may be raised or lowered, the vertical arms d' , d^2 , thereof

sliding respectively in the pipe B and over the gas pipe C. In this manner it will be seen that when the register Y is raised on its hinges so as to open the aperture α in the floor, the rod Q may be inserted as to its hooked end through the eye or loop g on chamber D and said chamber be thus raised up through aperture α above the level of the floor of the room as indicated by dotted lines in the drawings. When in this position a door f provided in the outer side of the arm d² of chamber D may be opened and the gas may be lighted at the burner C'.

By providing the chamber D with close walls and making its arm d' of a diameter to snugly fit the pipe B and the pipe F, of the proper diameter to admit only sufficient air to support combustion, it will be seen that should the gas be cut off at any time beyond the valve e, and said valve remain open, the escape of the gas from pipe C when again turned on would not take place into the room whereby an explosion might occur, but would be led off to the chimney. For this purpose I also make the door f air tight.

In order to steady the combustion chamber D in its vertical movement I attach to it at one end of its horizontal portion d a spring-rod h, the lower end of which plays through an eye or pipe B.

It will be seen that my invention is susceptible of considerable modification without material departure from its principles. For instance, the casing A may be omitted entirely and the device be supported on the wall Z, or said wall may be hollowed out to receive the parts in which case it would take the place of the casing. The chamber D might also be provided with an integral handle in lieu of the rod G, or the door f might be provided in its upper side and the chamber be made stationary.

Having thus described my invention, I claim—

1. In a heating apparatus, the combination with the gas supply pipe and an outlet pipe, each of said pipes having a vertical branch,

of a combustion chamber having an arm slidingly mounted on and communicating with each of said tubes, substantially as set forth. 50

2. In a heating apparatus, the combination with a gas supply pipe and an outlet pipe, each of said pipes having a vertical branch, of a combustion chamber having an arm slidingly mounted on and communicating with each of said pipes, said chamber being also provided with a door and an operating handle, substantially as set forth. 55

3. In a heating apparatus, the combination with a gas supply pipe and an outlet pipe, 60 each of said pipes having a vertical branch, of a combustion chamber having an arm slidingly mounted on and communicating with the outlet pipe, a burner tube mounted on said combustion chamber and having a burner 65 within the same, the lower end of said burner tube inclosing the vertical branch of the gas supply pipe, substantially as set forth.

4. In a heating apparatus, the combination with the curb having a hinged register and having an interior projecting ledge, of the casing having a projecting flange engaging the ledge of the curb, the gas pipe provided

with a valve, and having a vertical branch within the casing, the outlet tube adapted to 70 communicate with the flue and having a vertical branch within said casing, the combustion chamber having depending arms, one of which slides into the upper end of the vertical branch of the outlet tube, the other arm 75 of said combustion chamber being provided with a closed bottom, the brace, the burner tube mounted in said brace and extending through the closed bottom of the arm of the combustion chamber, the lower end of said 80 burner tube inclosing the vertical branch of the gas pipe, substantially as set forth.

In testimony whereof I affix my signature in presence of two witnesses.

J. W. UNDERWOOD.
